AERATOR FOR FURNACES

Fred D. Hoffman, Cleveland, Ohio, assignor
to Scientific Combustion Laboratories, Inc.,
Painesville, Ohio, a corporation of Ohio

Application September 23, 1931, Serial No. 564,537

1 Claim. (Cl. 110—74)

My invention relates to a method and apparatus for burning coal, coke or other solid fuels and is particularly concerned with a combustion chamber for efficient burning of such fuels and thorough utilization of the resultant heat.

Heretofore in the burning of coal and solid fuels, a very large percentage of the heat units of the fuel has been lost and wasted. This loss results not only from failure to free properly the volatile content of the fuel but also from improper aeration of the matter that is volatilized. The former failure is evidenced by the unduly large proportion of ash residue and the latter by the large volume of smoke and size and yellow color of the flame. Further evidence may be found by examination of the grate bars which will usually be found to be caked with carbonaceous deposits due to poor combustion or be burned badly or warped due to excess heat or too rapid and localized combustion.

The burning of solid fuels in the manner defined by my process frees all of the volatile and combustible matter from the fuel and completely aerates the gases and burns the resultant mixture and at the same time eliminates the difficulties above enumerated.

The combustion chamber and apparatus hereinafter described enables me to practice my process in any of the present types of furnaces without making any substantial change therein, and eliminates the need of the usual check draft in the stack.

The primary object of my invention, therefore, is the efficient combustion of solid fuels and economical utilization of heat therefrom and the accomplishment of these results with a comparatively simple and inexpensive apparatus.

A more specific object of my invention is to maintain the fire so as to form a large heat radiating surface thus effectively utilizing the heat units of the fuel.

Numerous advantages result from the practice of the method of my invention among which are the complete combustion of the cheapest and lowest grades of coal of either large size lump or exceedingly small particles and coal dust.

Another advantage of my invention resides in the fact that the rate of burning may be accurately controlled throughout a wide range, and instantaneous circulation of air and gases obtained so that the heat can be quickly increased or decreased.

Another advantage of my invention resulting from more nearly perfect combustion is the

elimination of smoke and a great reduction in the cinders and ash residue.

A very important object of my invention is to correlate the rate of evolution of the volatile gases from the fuel and the volume and distribution of secondary air to cause complete aeration and burning of the resultant mixture so that no combustible gas is lost and the cooling or conveying effects of excessive air are eliminated.

Another specific object is to preheat the air that is mixed with the evolved gases so that the gases may be burned quickly and close to the fuel bed and to direct the heat against the furnace walls so that stack losses are eliminated.

Another object of my invention is to burn the fuel evenly throughout the fire box and as effectively adjacent the furnace or retort walls as toward the central portion of the fire bed.

Another object of my invention is to burn the fuel in a manner such that excessive localized heats on the grate bars are eliminated.

Another important object is to protect the grate bars by conveying the heat away therefrom and completely recuperating the heat so conveyed away.

Still another object of my invention is to provide an inexpensive and durable apparatus for obtaining these results which may be easily and quickly installed in furnaces of the present type with slight or no change in the furnace structure, and which requires neither special skill for installation or operation, nor accessory equipment.

Another specific but important object of my invention is to maintain free circulation of air and gases in the furnace and to eliminate the danger of explosions due to accumulated gases in furnaces of the present type.

Other objects and advantages will become apparent from the following specification in which reference is made to the drawings by the use of reference numerals.

In the drawings, which illustrate a preferred form of apparatus suitable for carrying out my process:

Figure 1 is a side elevation of a furnace, a portion of the wall being cut away to show the interior of the firebox and the aerator with which my invention is particularly concerned;

Figure 2 is a reduced partial cross sectional view through the furnace taken on a plane indicated by the line 2—2 of Figure 1;

Figure 3 is an enlarged plan view of a form

of aerator embodying the principles of my invention;

Figure 4 is a front elevation of the aerator illustrated in Figure 3, the two separate sections in which the aerator is made being unbolted and separated for purposes of clearness in illustration;

Figure 5 is a cross sectional view of the aerator illustrated in Figure 3, taken on a plane indicated by the line 5—5;

Figure 6 is a cross sectional view of the aerator illustrated in Figure 3, and is taken on a plane indicated by the line 6—6 thereon;

Figure 7 is a perspective view of the aerator illustrated in Figures 3 and 4;

Figure 8 is a plan view of the fire combustion chamber of the furnace showing the general direction of the air current, the position of the aerator being shown in dot-dash line.

The furnace includes a combustion chamber 2 enclosed in an air chamber 4 in which the air is circulated and heated, and from which it is passed out through the usual conduits to various rooms or points of application. The bottom of the combustion chamber is spanned by a grating of bars 6 of any of the well known types. The combustion chamber is provided with a passage 8 for feeding fuel thereinto. This passage extends through the air chamber 4 and may be closed by a door 9. The lower wall of the passage forms a coking plate 10 of the furnace.

An air chamber 12 is positioned below the grates 6 and is of sufficient depth to retain a large volume of ashes or cinders without restriction of the passage of air through a passage 14, the size of the opening being controlled by means of a door 15. I have found it effective to locate the opening 14 well below the grates 6 for purposes later to be described.

The aerator with which my invention is more particularly concerned may be formed in two separate pieces, as illustrated in Figures 3 and 4, overlapping in the center so as to be slid relatively apart and together for convenience in fitting them into various sizes of combustion chambers. These sections may have complementary slots adapted to receive a bolt 16 for securing the two pieces in a fixed relative position.

The assembled aerator roughly is a frustro-pyramidal or frustro-conical shell or hood 18, surmounting a somewhat cylindrical or polygonal base, the walls of which base may be substantially vertical and comparatively low.

The particular form shown by way of illustration has a base 20 which is semi-circular in outline. The front face 22 of the aerator slopes inwardly of the base and upwardly. The adjacent faces 24 and 25 likewise slope toward the axis of the base and upwardly from the base so that the shell forms a surface substantially one half of a frustum of a six faced pyramid. It should be noted, however, that this specific number of walls or shape of faces is not necessary, the important feature being that the faces slope downwardly and outwardly so that the aerator is considerably larger at the base than at the top. The reason for these features will later be described.

Secured to or forming the top of the aerator is a head 32 which extends rearwardly of the body 18 and is preferably horizontal. The head 32 may be covered by a plate 33, shown particularly in Fig. 7. The height of this head above the base of the aerator is such that the aerator is installed, as illustrated in Figure 1. The faces of the body 1 are each provided with a large

number of openings 28, which are preferably parallel and extend in the direction of slope of the face, i. e., from the base substantially to the top of the faces, thus forming a grating, the grate bars being designated 30. The openings 28 may extend across the faces or in some other direction but experience has proven that the form illustrated is effective and permits a smooth flow of air upward along the underside of the walls of the body and exposes the grating bars 30 to the air evenly on each of their sides.

A distance back from the body 18 on the underside of the head 32 is a box-like chamber 34 having in the base a passage 36 which communicates the chamber with the space beneath the hood 15 and between the body 18 and the adjacent walls of the combustion chamber 2. The chamber 34 opens into the combustion chamber 2 of the furnace forming an elongated horizontal tuyère. The central portion of this opening may be closed, however, thus forming tuyères 38 and 40 near each end of the chamber 34. On each side of the body 18 are wings 42 and 44 which slope backwardly from the faces 24 and 25 respectively and upwardly to the head 32. These wings are provided with tuyères 46 which may be positioned as illustrated. These tuyères likewise communicate the space beneath the body 18 of the aerator and the remainder of the combustion chamber 2 of the furnace.

Superimposed upon the head 32, preferably at the outer ends and above the wings 42 and 44 are tuyères 48 and 50 which likewise communicate with the chamber 34 and through the chamber 34 with the space between the walls of the combustion chamber and body 18. The tuyères 48 and 50 may have sloping top walls 52. Both the tuyères 38 and 40 and tuyères 48 and 50 may discharge into the tuyères 38 and 40 and tuyères 48 and 50 may discharge into the combustion chamber horizontally. The tuyères 48 and 50, as illustrated tend to discharge downwardly due to the air currents impinging on the upwardly sloping top walls 52 and deflecting, though such is not noticeable in case of light drafts.

Briefly, my method includes continuously passing a relatively small volume of air slowly through the fuel bed to maintain the under stratum in a state of combustion and thus slowly to heat the upper stratum and evolve the combustible gases therefrom. The gases so evolved are regurgitated by a secondary stream or streams of preheated air of sufficient volume to permit complete combustion of the gases. The secondary air mixes with the gases easily, and, since it is preheated the resulting mixture ignites and burns rapidly. In order to utilize the resulting heat effectively, the secondary air currents are of such volume and so directed into the combustion chamber that slight pressure may result, forming a blanket over the fuel bed and preventing the gases from passing directly to the flue and escaping. Since air is an insulator or a poor conductor of heat, in the sense that while heat will not pass readily therethrough by conduction, it is a very efficient conveyor of heat, the secondary air is directed across the fuel bed so as to carry the burning mixture to and cause it to impinge upon the walls of the combustion chamber and follow therealong with a swirling motion and to deliver its heat directly against the combustion chamber walls. This same action renders the path of the burning stream through the combustion chamber more tortuous, thus allowing a longer period of time for the gases to burn therein.

5 My method further contemplates controlling the relative proportions of the primary and secondary volumes of air and the temperature of the latter by the shape of the under surface of the fire bed and particularly by maintaining the under surface sloped upwardly to the point of discharge of the secondary air.

The manner in which the aerator above described effects these results is as follows:

10 Assuming the fire bed within the combustion chamber 2 to extend from the grates 6 to the dot-dash line, indicated at 54, and the lower stratum of the fuel to be in a state of fusion, the rate of combustion is controlled by the size 15 of the passage 14. The cool outside air flows in along the bottom of the air chamber 12 following a path approximately as indicated by the arrows, to the rear end of the chamber 12. As it strikes the rear end of the chamber 12, it is deflected 20 against the heated grates 6 and its temperature increased, the grates 6 being cooled thereby. Part of this air infiltrates into and through the burning stratum maintaining combustion thereof to heat the upper stratum and evolve the gases. 25 Due to the upward slope of the aerator walls, however, less resistance is offered to the normal tendency of the heated air to rise. Consequently a large proportion of the air stream follows along the underside of the grates 6 and up under the 30 aerator, the portion of the grates 6 extending beneath the aerator being comparatively open and permitting free passage therethrough.

As the air rises along the under side of the aerator, a part of it passes through the passages 35 28 and through the fuel bed, maintaining the under stratum along the aerator in a state of combustion. The longitudinal grate bars 26 of the aerator permit easy upward flow of the air and are in turn maintained at a lower temperature 40 by giving up part of their heat to the air. The air is thus preheated to a higher degree. The grate bars of the aerator may extend in another direction than longitudinally but the flow of air is retarded somewhat as a result of passing 45 over a roughened surface. Furthermore, the bars are cooled more on the side toward the oncoming air than on the opposite side and there is a tendency to deflect more air through the fuel bed and cause eddy currents.

50 The air continues rising rapidly due to the pre-heating and passes into the openings 36 and out of the central tuyères 38 and 40 and the outer tuyères 48 and 50 into the combustion chamber. Part of the air also passes out of the tuyères 46 55 in the wings 42 and 44. The streams of air have considerable force as a result of thermal convection and issue from the tuyères as comparatively forcible streams. The streams of air from the central tuyères 38 and 40 may issue from the 60 central tuyères substantially horizontally across and close to the surface of the fuel bed, following a slightly upcurved path due to the natural tendency of heated air to rise. The walls of the combustion chamber 2 preferably slope inwardly 65 and upwardly away from the plane defined by the tuyères 38 and 40. This current of air passes over and close to the fire bed, as described, and is restricted by the opposite wall of the combustion chamber 2. In doing so part of the air 70 stream bends back above the original stream and part below as indicated by the arrows 55 and 58 respectively. Part also tends to follow back along the walls of the chamber 2.

The streams of air from the tuyères 48 and 50 75 tend to pass along and close to the upper sur-

face of the fuel bed, following along the walls of the chamber, as illustrated in Figure 8. These streams of air meet each other and the air from the tuyères 38 and 40 and form in the horizontal plane reversely rotating swirls. At the 75 same time there is a tendency for all the air to swirl in a vertical plane, the underside of the swirl being directed toward the rear wall of the combustion chamber and the upper returning. Thus the gases are pulled into the air streams 10 and forcibly impinged against and rolled along the combustion chamber walls. The air from the tuyères 46 has a tendency to assist this effect of the streams from the tuyères 48 and 50.

Since part of the fire bed rests against the tuyères 46, part of the air therefrom passes through the fuel, causing combustion thereof and thus evolving gases near the feeding door of the furnace. These gases are blanketed down by the incoming air streams and caught in the swirling 20 streams and burned as described. Due to the steepness of the under slope of the wings 42 and 44, only a small proportion of the secondary air stream passes therethrough into the fuel bed. However, due to the sloping outer surface of the 25 aerator, the fuel bed is comparatively shallow and sufficient air will pass therethrough to coke the fuel. It should be noted that this aerator is preferably placed adjacent to the feeding door 9 and fuel fed into the furnace is merely shoveled onto 30 the plate 32. As the fuel is shoved off from the plate 32, it falls onto the sloping surface of the aerator which causes it to spread outwardly as it progresses downwardly. Thus as fresh fuel is heated and volatilized, the gases pass across the 35 entire combustion chamber and are burned. Furthermore, fusing and burning embers instead of fresh fuel are presented to the combustion chamber walls. Thus at no time is fresh fuel against the walls which would carry away the heat rapidly and prevent ignition.

The inward slope of the upper portion of the fire box tends to reflect radiated heat onto the fuel bed, thus assisting in burning the gases.

In summation of some of the effects of the 45 sloping surface of the aerator it should be noted that the fresh fuel is spread over a large area and is supplied with air to thoroughly coke it and at the same time a large surface of glowing 50 embers is left uncovered away from the door so that the heat may be effectively radiated and conveyed and the evolved gases burned.

Another important reason for sloping outwardly the walls of the aerator resides in the fact 55 that the thickness of the fuel bed and direction of air therethrough are such as to maintain efficient combustion and effectively apply the resultant heat. For example, the aerator illustrated in Figure 1 projects well out into the combustion chamber, the base extending to or slightly past 60 the center thereof. In many cases the base 20 should extend about two-thirds to three-fourths of the way across the combustion chamber.

The fuel bed is then of much less thickness 65 toward the bottom, especially in the direction of flow of air through the fuel bed from the aerator. Therefore, the already glowing embers may be more efficiently burned and the heat directed against the combustion chamber walls and utilized rather than pass out of the stack and be lost.

In this manner a somewhat hood-shaped bed of fuel is maintained. If a more intense heat is desired, it is only necessary to open the passage 75

14 and permit more air to enter the chamber 12. This causes more rapid combustion and consequently tends to heat the aerator and grates more. Concurrently with the rise in temperature 5 of the grates, the air is preheated more and tends to rise more rapidly and draw in a larger volume. Thus the primary and secondary air currents are correlated and the use of a check draft is unnecessary, the air always circulating freely regardless 10 of volume.

Thus far I have described my invention in conjunction with a manually fired furnace and natural draft. Obviously it is very effective when used with an automatic stoker, the fuel being 15 fed onto the plate 33 continuously and consequently continuously progressing downwardly and outwardly from the plate and burning as described. If the stoker is of the forced draft type, the air conduit may discharge into the chamber 20 beneath the member 10. The use of such stokers with my invention is sufficiently clear without illustration.

It is apparent that I have invented a method and apparatus for burning solid fuels which I

have found may be used effectively with numerous devices employing heat other than the particular furnace shown by way of illustration.

I claim:

A supplementary grate for use in a furnace 5 having a horizontal grate and a fire box rising therefrom with a fuel feed opening at the side thereof above the horizontal grate, said supplementary grate comprising a plurality of sections presenting a surface to the fuel bed approximately 10 in the shape of a sector of a cone and its base portion being shaped to fit upon the horizontal grate bars and the side walls to engage the side walls of the fire box, having at its upper portion when assembled a transverse passage for receiv- 15 ing air from the inner side of the supplementary grate having tuyère-like orifices opening over the fuel bed, and from which air is discharged from said passage, said sections being secured together and relatively adjustable to increase or decrease 20 the width of the same, and the cone sector surface having upright slot-like openings through which air may pass to the fuel bed.

FRED D. HOFFMAN.
